WALKING HEEL

Creed A. Wiltrot, St. Paul, Minn.

Application May 13, 1949, Serial No. 92,979

7 Claims. (Cl. 128—83.5)

1

My invention relates to an improvement in walking heel of a type useful in conjunction with leg casts and the like.

In recent years it has become rather common practice to encase an injured leg in a cast and to provide a stirrup or brace on the cast so that the injured person may walk without injuring the cast or the injured leg. By this method patients with broken legs, fractures or the like are able to walk much sooner than would otherwise be possible without the use of crutches or the like.

A feature of the present invention lies in the provision of a walking heel which may be embedded directly in the cast to form an integral part thereof. The heel is so designed as to project below the cast and below the heel of the injured foot so as to support the weight of the injured person through the cast. The heel is preferably circular at its base so that the foot may be moved in any direction with ease. This arrangement differs somewhat from the usual practice in which the stirrup sometimes employed comprises a U-shaped brace which extends on opposite sides of the cast and below the heel portion of the cast and is thus provided with a transversely extending tread or bearing portion.

A feature of the present invention lies in the provision of a walking heel having a series of anchoring members embedded in the body thereof which may permit the heel to be embedded in the cast. These wires or reinforcing members form a firm connection between the heel and the cast and extend outwardly from the heel in various directions so as to form a firm anchor for connecting the heel to the cast.

An added feature of the present invention lies in the provision of a heel which may, if desired, be secured to a stirrup or brace somewhat similar to that now commonly employed. In this form of construction the heel is made of the same general shape and design as in the previously described construction, but an anchoring plate is embedded within the heel to which the brace or stirrup may be removably connected.

These and other objects and novel features of my invention will be more clearly and fully set forth in the following specification and claims.

In the drawings forming a part of my specification:

Figure 1 is a perspective view of a portion of a cast showing my walking heel embedded therein.

Figure 2 is a top plan view of the heel illustrated in Figure 1.

Figure 3 is a perspective view of the anchoring

members showing their relationship when embedded within a heel.

Figure 4 is a side elevation view of the heel of Figure 1 showing the construction thereof.

5 Figure 5 is a perspective view of a modified form of walking heel construction.

Figure 6 is a cross-sectional view through the walking heel illustrated in Figure 5.

10 Figure 7 is a top plan view of the heel illustrated in Figure 6.

Figure 8 is a top plan view of a modified form of the heel shown in Figures 6 and 7.

Figure 9 is a sectional view through the heel shown in Figure 8.

15 Figure 10 is a sectional view through another modified form of heel construction.

The walking heel A is designed to be embedded in the lower end of a cast B of the type used to encase a leg which has been broken or otherwise injured. The cast B is formed of plaster of Paris or similar material and holds the portions of the injured limb in proper location during the healing action. The heel A is employed so that the patient may be ambulatory before the leg has mended.

20 The heel A includes a rounded body 10 of gum rubber or similar material which is preferably tapered slightly in form. The upper surface 11 of the heel body 10 is usually substantially flat and is of slightly larger diameter than the bottom surface 12. The bottom surface 12 is usually provided with a shallow indentation 13 at the center of the heel and a series of ring shaped grooves 14 concentric with the periphery of the heel encircling the indentation 13. These grooves 14 and the center indentation 13 create a gripping effect on a surface such as a floor or walk and prevent the heel from slipping in any direction.

25 The upper surface 11 of the heel is preferably provided with four equally spaced substantially cylindrical cavities which are preferably substantially equi-distant from the center of the heel. The two opposed cavities 15 are similar in size and shape and a second opposed pair of cavities

30 16 are also somewhat similar in size and shape, although the cavities 15 and 16 need not necessarily be of the same size. A pair of oppositely disposed shallow recesses 17 of generally rectangular shape are provided in the upper surface 11 outwardly of the cavities 16 and centered with respect thereto. A central shallow depression 19 is provided at the center of the upper surface 11.

35 16 A pair of crossed anchoring members 20 and 21 are embedded within the heel body 10 to extend outwardly from the heel in a substantially radial

55

direction. These anchoring members 21 are preferably formed as illustrated in Figures 3 and 4 of the drawings and are embedded in the material forming the heel body 10. The center portion 22 of the anchoring member 20 is connected by off-sets 23 and 24 to the ends 25 and 26 of this anchoring member so that the ends 25 and 26 may be substantially flush with the upper surface 11 of the heel while the center portion 22 is located toward the bottom surface 12 thereof. Similarly the anchoring member 21 is provided with a center portion 27 which is connected by off-sets 29 and 30 to the ends 31 and 32 so that the central portion 27 may be embedded deeply in the bottom of the heel while the ends 31 and 32 are substantially flush with the upper surface 11. The ends of the anchoring members are preferably on the same plane, but the off-sets are of proper length to permit the reinforcing members to cross as illustrated.

As will be noted from Figure 2 of the drawings the reinforcing members 20 and 21 are arranged so that the ends of these members are substantially a distance apart equal to the diameter of the upper surface 11 of the heel. In other words the anchoring members 20 and 21 do not cross at right angles but are arranged at a somewhat lesser angle apart so that the reinforcing members are not unduly wide. As a result the heel may extend most of the width of the cast if desired without causing the anchoring members to project from the cast.

The apertures 15 and 16 provide somewhat greater flexibility in the heel and increase the cushioning action. The molds in which the heels A are formed are designed to form either the type of construction illustrated in Figures 1 to 4 of the drawings, or the modified forms of construction which will be later described. In certain of the modified forms of construction the holes 15 or 16 act to accommodate bolts or other fastening means.

The use of the walking heel A is believed obvious from an examination of Figure 1 of the drawings. When the cast B is formed of plaster of Paris or similar material, the walking heel is partially embedded in the plaster so that the anchoring arms or rods 20 and 21 extend into the body of the cast and form a firm anchor for the heel. As a result the patient may walk long before the healing operation is completed.

In the form of construction illustrated in Figures 6 and 7 of the drawings the heel C is of the same general shape as the heel A and may be actually formed in the same mold. However, the heel C is provided with an anchoring strip 33 which is U-shaped in cross section and includes a generally circular disc 34 having a pair of upwardly extending spacing arms 35 and 36 at opposite sides thereof. The disc 34 is preferably notched about its periphery with spaced notches 37 and may be provided with a central aperture 39 which permits the rubber to extend through the body of the plate. The disc 34 is likewise provided with diametrically opposed apertures 40 near the outer periphery of the disc and somewhat similarly disposed threaded apertures 41 closely adjacent to the upwardly extending arms 35 and 36. The upper ends of the arms 35 and 36 may terminate slightly below the upper surface 42 of the heel body 43. This permits the material forming the heel to be compressed slightly when the heel is attached to a stirrup or brace.

In Figure 5 of the drawings I disclose a stirrup

or brace 44 of a type which may be used in connecting the heel C to the cast D. It will be noted that the stirrup 44 includes a transversely extending portion 45 and a pair of parallel upwardly extending arms 46 and 47. Transverse clamping members 49 may be riveted or otherwise attached to the upper ends of the arms 46 and 47. The heel C is attached to the cross member 45 as indicated in Figures 5 and 6 of the drawings.

As best noted in these figures, cap screws or bolts 50 extend through the cross member 45 of the stirrup and extend through the spaced recesses 51 in the heel body 43. These cap screws 50 also extend through the threaded apertures 41 in the disc 34. By tightening these cap screws the upper ends of the arms 35 and 36 are drawn tightly against the under surface of the cross member 45 of the stirrup so as to firmly connect the heel to the stirrup. The resilience of the heel body permits the desired compression and cushioning action, but at the same time the anchoring plate is firmly connected to the stirrup.

20 The heel C is similar to the heel A in that a member is embedded within the body of the heel to form an attachment with a cast. In the first described construction the members embedded in the heel extend into the body of the cast in such a way as to prevent movement of the heel relative to the cast. In the construction shown in Figures 6 and 7, the heel is connected to a stirrup or brace, which in turn is fastened to the cast. This is the more conventional way of fastening the heel, but is obviously somewhat more complicated than the previously described arrangement.

25 In Figures 8 and 9 I disclose a modified form of construction E which is designed for attachment to the brace or stirrup 44. The brace or stirrup is identical to that previously described and includes a cross member 45 to which the heel E is attached. The stirrup includes generally parallel side members 46 and 47 for holding the heel to the cast.

30 The heel E is provided with a U-shaped reinforcing strip 51 which extends into the body of the heel to provide a means of connecting the heel to the stirrup 44. The strip 51 includes the transversely extending center portion 52 and a pair of upwardly extending end arms 53. The arms 53 act similarly to the arms 35 and 36 of the heel C. A transversely extending strip 54 is spot welded or otherwise attached to the strip portion 52 to provide an additional anchoring area, the cross strip 54 is provided with apertures 55 therethrough, and the strip portion 52 is provided with threaded apertures 56 therethrough. The apertures 56 are aligned with apertures 57 in the heel body 59 and are designed to accommodate cap screws 60 or other suitable fastening means, by means of which the central portion 52 of the strip 51 may be connected to the cross member 45 of the stirrup 44. In this construction as in the previously described construction the arms 53 preferably terminate slightly below the upper surface of the heel body 59 so that the tightening of the cap screws 60 tends to compress the portion of the heel engaging the cross member 45 of the strip.

35 In Figure 10 of the drawings I disclose another modified form of construction of heel. This heel which is designated in the drawings by the letter F includes an anchoring plate 61 which may be any desired shape or size and may be either of

disc-like outline or may be rectangular. Openings such as 62 are preferably provided in the disc 61 so that the rubber of the heel may be joined through the plate. Threaded apertures 63 are provided in the plate 61 in alignment with apertures 64 through the body 65 of the heel. Spacing sleeves 66 are provided between the plate 61 and the upper surface of the heel body so as to hold the plate 61 in properly spaced relation to the cross bar 45 of the stirrup 44.

Bolts or cap screws 67 extend through the cross bar 45, through the sleeves 66, and through the plate 61 to hold the plate in fixed relation to the cross bar 45. Thus the anchoring plate 61 is held in definite fixed relation to the stirrup 44.

It will be seen that all of the heels illustrated are very similar in form and may be made with the same molding apparatus. The body of the heel compresses sufficiently to cushion the shock and the heel is held in place either by embedding arms of the heel into the cast or by securing the heel to a stirrup, which in turn is connected to the cast. All of the heels employ anchoring members of some type which are embedded in the body of the heel and form a firm connection therewith.

In accordance with the patent statutes, I have described the principles of construction and operation of my walking heel construction, and while I have endeavored to set forth the best embodiments thereof, I desire to have it understood that these are only illustrative thereof and that obvious changes may be made within the scope of the following claims without departing from the spirit of my invention.

I claim:

1. A walking heel for use in conjunction with a cast, the heel including a body of resilient material having upper and lower surfaces, anchoring means embedded within the resilient material between said surfaces and anchored in place by resilient material overlying and underlying the anchoring means, and means carried by said anchoring means for connecting said anchoring means to the cast.

2. A walking heel including a body of resilient material having anchoring means embedded therein between the upper and lower surfaces thereof, said anchoring means projecting from opposite sides of said resilient body.

3. A walking heel comprising a body of resilient material having anchoring means projecting therefrom, said anchoring means being permanently molded in and embedded within said body of resilient material to form an integral part thereof.

4. A walking heel including a body of resilient material, a pair of anchoring members embedded within said material and projecting therefrom, said arms intersecting within said body of resilient material and extending outwardly from said body in diverging relation.

5. A walking heel including a body of resilient material, an anchoring plate embedded within said material between the upper and lower surfaces thereof, and a cross member to which said heel is attached, and bolts extending through said cross member and into said reinforcing member to connect said heel to said cross member.

6. A walking heel including a body of resilient material having an anchoring plate embedded within the same between the upper and lower surfaces thereof, up-turned arms on said plate, apertures in said resilient body between said up-turned arms, and threaded apertures in said reinforcing member aligned with said apertures.

7. A walking heel comprising a resilient body having top, bottom and side surfaces, and a rod-like anchoring structure provided with a plurality of arms extending in at least three different directions, at least a portion of said anchoring structure residing inwardly of said side surface and between said top and bottom surfaces, said arms being adapted to be embedded in the material forming a cast for a person's limb.
